UNITED STATES PATENT OFFICE.

WELLINGTON MILLS, OF SHILOH, OHIO.

DESIGN FOR A PLOWSHARE.

SPECIFICATION forming part of Design No. 26,906, dated April 13, 1897.

Application filed December 4, 1896. Serial No. 614,495. Term of patent 14 years.

To all whom it may concern:

Be it known that I, WELLINGTON MILLS, a citizen of the United States, and a resident of Shiloh, county of Richland, State of Ohio, 5 have invented certain new and useful Designs for Plowshares, of which I hereby declare the following to be a full, clear, and exact description, such as will enable others skilled in the art to which it appertains to make and 10 use the same.

Figure 1 is a perspective view of the under side of a plowshare, showing my design. Figs. 2 and 3 are transverse sections upon lines *a a* and *b b*, showing additional features of the 15 design, these three views being deemed essential to fully illustrate my design.

The leading feature of my design is a curved plowshare, along the bottom edge of which from the heel to a point near the front extends the narrow surface 1.

The surface is terminated on the inner edge by a vertical face 2, forming a right angle therewith, and a curved surface 9 limits the outer edge, as clearly shown in the sectional

figures. The raised surface is not parallel 25 with the inner surface 3 of the share, but forms a slight elevation of about one-sixteenth of an inch at the outer extremity 4, and it diminishes to nothing at the front extremity 5, and merges into the surface of the share in 30 the form of a wedge.

The front edge of the share is also provided with the narrow raised surface 6, terminated on one side by a vertical plane 7 and on the outer edge by the curved plane 8. Thus the 35 share presents a sharp angular edge in front and side. In other respects the share is shaped in the usual manner.

What I claim is—

The design for a plowshare as herein shown 40 and described.

Signed at Cleveland this 28th day of November, 1896.

WELLINGTON MILLS.
